UNITED STATES PATENT OFFICE.

STEPHEN T. SMITH, JR., OF STAMFORD, CONNECTICUT, ASSIGNOR TO UNDERWOOD TYPE-WRITER COMPANY, OF NEW YORK, N. Y., A CORPORATION OF NEW JERSEY.

STENCILING-MACHINE.

No. 887,438.

Specification of Letters Patent.

Patented May 12, 1908.

Application filed February 12, 1908. Serial No. 415,516.

To all whom it may concern:

Be it known that I, STEPHEN T. SMITH, Jr., a citizen of the United States, residing in Stamford, in the county of Fairfield and State of Connecticut, have invented certain new and useful Improvements in Stenciling-Machines, of which the following is a specification.

This invention relates to stenciling machines for use with typewritten stencils, and more particularly to the means for delivering the sheets from the machine.

The stencil is usually wrapped around an inking cylinder, and the sheets to be stenciled upon are passed between said cylinder and a pressure roll. The machine is usually equipped with stripping tongues placed at the ends of the stencil cylinder, to lie between the stencil and the sheets to be stenciled upon, so as to separate or strip the latter gently from the stencil sheet, as the cylinder revolves. The stripping is rendered necessary because of the adhesive character of the ink usually employed. In some cases the sheets to be stenciled upon are too narrow to be engaged by both of said stripping tongues; and it is also sometimes desired to pass narrow sheets through the middle portion of the machine, so that their side edges are not caught by either of the stripping tongues.

The object of my invention is to provide simple, inexpensive and effective means for stripping narrow sheets from a stencil cylinder, without however rendering the machine less valuable for use with wide sheets.

At the delivery side of the cylinder, I mount a pair of stripping fingers which extend towards each other along the cylinder, and each of which is longitudinally fluted with its concave side lying close to the cylinder, so that its convex side may insinuate itself between the cylinder and the leading edge of the paper which has been stenciled upon, as it emerges from the machine, and gently strip the paper from the stencil cylinder. Each of said strips is swiveled at its outer end, so that it may be adjusted at different angles relatively to the cylinder, to obtain the best results, and also so that it may be swung back entirely out of the way when wide sheets are being run through the machine.

My invention is shown applied to stenciling machines of the kind disclosed in United

States Patent No 832,217 of October 2, 1906, in which stripping tongues for wide sheets of paper curve under the stencil cylinder past the ends of the pressure roll; and my novel stripping fingers are preferably pivoted to the rear ends of said tongues.

Figure 1 is a sectional diagrammatic elevation of a stenciling machine of the kind disclosed in said patent, showing the novel stripping finger in full lines in working position, and in dotted lines in a position of disuse. Fig. 2 is a plan of the stripping devices.

The stenciling machine usually comprises a stencil cylinder 1, a pressure roll 2, a feed board 3 and a directrix plate 4 curving around the under side of the cylinder at the introductory side thereof. A narrow sheet 5 to be stenciled upon is shown as passing through the machine, said sheet being too narrow to be engaged by the stripping tongues 6, 7 usually placed at the ends of the cylinder 2, as set forth in said patent. The side borders of the narrow sheet 5 are engaged by the sides of a pair of stripping fingers 8 which extend toward each other along the cylinder 1. Each of the fingers is fluted, and its concave side lies close to the cylinder and near the pressure roll 2, as at Fig. 1; the lower edge 9 of each finger being close to the cylinder, so as to enter between the cylinder and the leading edge of the sheet and strip the latter therefrom; the convex outer side of the stripper acting like a wedge for this purpose. The strippers are preferably mounted upon the rear ends of the stripping tongues 6, 7, the strippers being swiveled at their outer ends to the rear ends of said tongues as at 10, so that the strippers may be adjusted, as for instance to the dotted line position, as at Fig. 2, to suit different kinds of sheets being run through the machine; and also to enable the strippers to be swung rearwardly entirely out of the way, as at Fig. 1, when wide sheets are being stenciled.

It will be understood that one stripping finger may be used for one side edge of the sheet while the other side edge is engaged by the usual stripping tongue 6 or 7; the other stripping finger being swung back to the dotted line position at Fig. 1.

Having thus described my invention, I claim:

1. In a stenciling machine, the combination with a stencil cylinder and a pressure

110

roll, of a stripping finger arranged on the delivery side of the cylinder and extending along the stencil cylinder and close thereto; said stripping finger swiveled on its outer end 5 to permit it to be swung away from the stencil cylinder, and being longitudinally fluted and its concave side being presented to the periphery of the cylinder.

2. In a stenciling machine, the combination with a stencil cylinder and a pressure roll, of a pair of stripping fingers mounted on 10 the delivery side of the cylinder and extending towards each other along the stencil cylinder and close thereto; each finger movable 15 independently of the other away from the cylinder to a position of disuse.

3. In a stenciling machine, the combination with a stencil cylinder and a pressure roll, of a pair of stripping fingers mounted on 20 the delivery side of the cylinder and extending towards each other along the stencil cylinder and close thereto; each of said stripping fingers being swiveled on its outer end to permit it to be swung away from the

stencil cylinder independently of the other 25 stripping finger.

4. In a stenciling machine, the combination with a stencil cylinder and a roll to press the sheets against the cylinder, of a stripping tongue curving under the cylinder 30 to engage the side edge of a sheet of paper, and a stripping finger mounted on the rear end of said tongue and extending along the stencil cylinder and close thereto.

5. In a stenciling machine, the combination with a stencil cylinder and a roll to press the sheets against the cylinder, tongues 35 extending along the ends of said roll close to said cylinder to keep the side edges of the paper out of contact with the stencil, and 40 stripping fingers swiveled upon the rear ends of said tongues to extend along the cylinder and close thereto and to swing rearwardly away from the cylinder.
